UNITED STATES PATENT OFFICE

WALTER M. WOLF, OF CHICAGO, ILLINOIS

DESIGN FOR AN ASH RECEPTACLE FOR SMOKERS' USE

Application filed February 20, 1931. Serial No. 38,748. Term of patent 14 years.

To all whom it may concern:

Be it known that I, WALTER M. WOLF, a citizen of the United States, residing at Chicago, in the county of Cook and State of Illinois, have invented a new, original, and ornamental Design for Ash Receptacle for Smokers' Use, of which the following is a specification, reference being had to the accompanying drawing, forming a part thereof. The figure is a perspective view of the ash receptacle for smokers' use, showing my new design.

I claim:

The ornamental design for an ash receptacle for smokers' use, as shown.

WALTER M. WOLF.
